Ward, Crosby and Smith

UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT.

DOOR LATCH.

Application filed April 28, 1922. Serial No. 557,124.

To all whom it may concern:

Be it known that I, RAYMOND G. MOORE, a citizen of the United States, and resident of Bridgeport, county of Fairfield, State of Connecticut, have invented certain new and useful Improvements in Door Latches, of which the following is a specification.

The invention relates to improvements in door latches and particularly to latches adapted for use in connection with automobile doors. My invention enables the occupant of an automobile, by means of a simple and effective mechanism, to lock, or to render inoperative, the handle or handles by which a door or doors of the car may be opened from the outside. Thus in a closed car having, for example, four doors, the operator may lock the outside handles of three of the doors so that a person on the outside cannot open the same, the hand levers or other means for retracting the bolts of the door latches from the inside remaining operable. With such an arrangement the one door, the outside handle of which is not thus locked, may be locked by the owner when he leaves the car, by a key operated lock operable from the outside or by any other suitable means. In this case, therefore, the owner has only to lock the one door referred to upon leaving the car in order to prevent unauthorized persons from entering the same, the outside handles of the other doors having previously been locked against operation, by manipulation of the devices on the inside of the car, referred to.

An object of the invention is the provision of improved, effective and simple devices of the character referred to. Another object is the provision of an improved construction whereby the inside and outside means for retracting the bolt, usually a hand lever on the inside and a rotatable handle on the outside, will each be firmly maintained in the same angular positions, when the same are not in use. The hand lever on the inside will preferably be firmly maintained in a vertical position when it is not in use and the outside door handle will preferably be maintained in a horizontal position, when it is not in use.

Other objects of the invention comprise the provision of various combinations of parts and details of construction, all as will be more fully set forth in the following

specification and particularly pointed out in 55 the appended claims.

In order that the invention may be more clearly understood attention is hereby directed to the accompanying drawings forming part of this application and illustrating one 60 embodiment of the invention.

In the drawings, Fig. 1 is a front elevation of a door latching mechanism embodying the invention, the bolt being shown in its forward or operative position; 65

Fig. 2 is a similar view, on an enlarged scale, the cover plate of the bolt casing being partly broken away, and the bolt being shown as retracted by operation of the outside handle; 70

Fig. 3 is a view similar to that shown in Fig. 2, with the bolt, however, in its forward position and the member in which the outside handle is inserted locked against operation, and 75

Fig. 4 is an enlarged section taken on line 4—4 of Fig. 1.

Referring to the drawings, the construction is illustrated as comprising a plate 1 and a cover plate 2, which constitute a casing within which the bolt 3 is slidably mounted. The cover plate may be secured to plate 1 in any suitable manner, as by the provision of slots 4, 4, in plate 1 through which flanges of the cover plate may be extended. Plate 1 is illustrated as provided at its forward edge with a flange 5 through an opening in which the nose portion of the bolt slidably extends. 80

A spring 6 is shown as having one end of 90 the same secured to plate 1 while the other end bears against the rear end of the bolt which is thus normally spring pressed into or towards its operative position. It will, of course, be understood that plate 1 is intended to be secured to the inner face of a door in such position that the nose of bolt 3 will enter a suitable keeper recess in the door frame when the door is closed, cover plate 2 being mounted in a recess in the door. 95

In the construction illustrated the bolt may be retracted against the pressure of spring 6 by means of a hand lever 7 which is illustrated as pivoted at its lower end at 8 to a plate 1. Lever 7 extends through a slot 9 in the bolt and is adapted to bear against a shouldered portion indicated at 10, at the rear of the bolt, when the latter is to 100

be retracted by means of the hand lever. Hand lever 7 is shown as spring pressed into its forward position by means of a suitable spring 11 suitably secured to plate 1.

5 The hand lever may be provided with an inwardly extending portion at its upper end (not shown) which may be grasped by the hand to retract the bolt in the usual manner.

The bolt may be retracted from the outside by a handle, which I have not deemed it necessary to illustrate, the handle having a squared shank adapted to fit within a squared socket 12 in the usual manner. The squared opening 12 is formed through the

15 circular web portions 13 of a member 12¹ which is rotatably mounted between plate 1 and the downwardly extending portion 2¹ of cover plate 2. This member is shown as having an annular flange 14 which may be 20 rotatably mounted at its opposite ends in plate 1 and portion 2¹ of the cover plate 2.

This rotatable handle-operated member 12¹ is provided with a portion or portions which, in the form of construction illustrated, will bear against hand lever 7, when the outside handle is turned, to force the hand lever rearwardly to cause the latter to retract the bolt. In the form of construction shown member 12¹ is double acting, that 30 is partial rotation in either direction will serve to force hand lever 7 rearwardly against the pressure of spring 11.

In the preferred construction member 12¹ is provided with upwardly and downwardly 35 extending projections 15, 16, which have curved operative surfaces 17 and 18 respectively. These surfaces 17 and 18 are connected by a concavely curved surface 19.

When the outside handle is turned in one 40 direction the surface 17 of arm 15 will bear against and move over the forward surface of hand lever 7 to swing the same rearwardly, and when the outside handle is turned in the other direction the surface 18 of the lower arm 16 will correspondingly engage the forward surface of the hand lever. In the preferred form of construction a roller 20 is carried by the hand lever, this 45 roller being rotatably mounted therein in any desired manner. With this construction the working faces of member 12¹ will engage roller 20, to swing the hand lever and the bolt rearwardly, when the outside handle is turned in one direction or the other. In 50 Fig. 2 the outside handle has been rotated in such a direction as to cause surface 17 to engage and rotate roller 20, the hand lever and bolt accordingly being retracted.

When the bolt is in its normal forward 60 position, as shown in Fig. 1, roller 20 of the hand lever will engage within the concavely curved surface 19 of the member 12¹. The hand lever will thus be held in a vertical position, spring 11, (and shoulder 10 of bolt 3), pressing against the same on one

side and the curved portion 19 of member 12¹ bearing against roller 20 carried by the lever on the other side. The handle member, the shank of which is mounted within socket 12, will also be held in a horizontal 70 or other desired angular position because of the seating of roller 20 within the curved portion 19 of member 12¹. If the outside handle member tends to rotate in either direction, the pressure of roller 20 against surface 17 or surface 18 of member 12¹ will tend to turn member 12¹ back into its normal position in which roller 20 seats within the centrally located recess 19.

The construction by which member 12¹ and the outside handle may be locked against operation will now be described. A dog 21 is pivotally mounted at one end on a stud 22 which is secured to plate 1 and extends outwardly, that is, towards the outside of the door, therefrom. Stud 22 may be provided at its outer end with a head 22¹ against which dog 21 bears. A spring washer 23 is preferably positioned about stud 22 between plate 1 and the inner surface of dog 21, so as to provide a friction element to prevent dog 21 from swinging too readily about stud 22.

Dog 21, in the form of construction illustrated, is provided, adjacent its opposite end, with an upwardly extending nose 24 which is adapted to fit within a similarly shaped recess 25 which extends upwardly from the lower surface of the downwardly extending portion 16 of member 12¹. When 100 nose 24 is positioned within recess 25 member 12¹ will be locked against rotation in either direction. Equivalent locking surfaces may of course be used.

Dog 21 may be swung into operative and inoperative positions by means of a suitable hand operated device extending inwardly from the inner surface of the door. As shown, this may comprise a spindle 26 extending through and rotatably mounted 110 within a bearing member 27 which is located in a suitable opening in plate 1.

Spindle 26 has a pin 28 extending outwardly, that is towards the outside of the door, from the outer surface 26¹ of spindle 26. This pin is mounted eccentrically with respect to the axis of spindle 26. Dog 21 is provided with a slot 29 therethrough through which pin 28 extends. The end portion 26¹ of the spindle with pin 28 thereon constitute in effect a crank disc with a crank pin mounted thereon. In Figs. 1 and 2 of the drawings the pin 28 is shown in its lower dead center position. When the pin is in this position dog 21 will be inoperative, nose 24 being out of position to interfere with the movement of the lower portion of arm 16 of member 12¹ past the same.

When, however, the outside handle is to be locked against operation, the bolt 3 be-

ing in its forward or operative position and arms 15 and 16 of member 12¹ extending in their normal vertical position, spindle 26 may be turned by means of a knurled head 30 thereon. Such rotation of head 30 will swing dog 21 upwardly, in a direction of counter-clockwise rotation, referring to Figs. 1, 2 and 3, and nose 24 will move into recess 25 of member 12¹, as is shown in Fig. 3. Member 12¹ will now be locked against rotation in either direction.

An effort to rotate member 12¹ in a counter-clockwise direction, referring to Fig. 3, will merely result in the transmission of pressure through dog 21 against the stud 22 on which the dog is pivotally mounted. Similarly an attempt to rotate member 12¹ in the opposite or clockwise direction will simply result in exerting a pull upon the stud 22, the pressure of arm 16 of member 12¹ against nose 24 having no effect to rotate dog 21 out of locking position. Pin 28 preferably swings from a position slightly in advance of its lower dead center to a position slightly to the rear of its upper dead center position, when knob 30 is rotated as stated to swing the dog into its locking position.

Dog 21 will be held in its locking position, because of the fact that pin 28 is substantially in its upper dead center position and also because of the friction exerted on dog 21 by the spring washer 23. When member 12¹ is to be unlocked, it is, of course, simply necessary to turn knob 30 back sufficiently to replace dog 21 in its inoperative position shown in Figs. 1 and 2.

The construction may, of course, be arranged to permit knob 30 being turned in either direction to move dog 21 into locking position. In the embodiment shown, knob 30 is arranged to turn in only one direction to operate dog 21, so that a positive stop will be provided for the parts when pin 28 has reached its lower inoperative position and engages against the end of slot 29.

When nose 24 is in locking engagement within recess 25 pressure exerted against the nose by either wall of recess 25, when effort is made to turn member 12¹ in either direction, will be exerted substantially in the direction of pivot 22, or the direction from pivot 22. That is, with such an arrangement, there will be substantially no component of the force exerted against nose 24 which will tend to swing dog 21 about its pivot 22, out of its locking position.

It will be noted that hand lever 7 and handle-operated member 12¹ mutually coact, when in their normal unoperated positions, to maintain each other in desired angular positions. In my application Serial No. 550276, filed April 7, 1922, an arrangement is described and claimed whereby the hand lever is normally held in a desired angular

position while in its position of rest, and the handle-operated member for retracting the bolt is also normally held in a desired angular position. Any claims which may be generic to the construction there described and to the construction described herein, in connection with this feature, will be made in said application, Serial No. 550276.

It should be understood that while I have described certain forms and features of the invention with particularity, the invention is not limited to the exact details which have been described, but that various modifications may be employed as will be clear to those skilled in the art after reading this specification, the scope of the invention being indicated by the accompanying claims.

What I claim is:

1. In a door latch, the combination of a support, a bolt movable thereon, hand operated means, operable from the inner side of the door, for retracting the bolt, hand operated means, operable from the outer side of the door, for moving said first named hand operated means to retract the bolt, and means operable from the inside of the door for locking the second named hand operated means against movement while leaving the first named hand operated means operative.

2. In a door latch, the combination of a support, a bolt movable thereon, a hand lever pivoted to said support and adapted to retract the bolt, hand operated means, rotatable in either direction, for moving said hand lever to retract the bolt, and means for locking said hand operated means against movement while leaving said hand lever operative.

3. In a door latch, the combination of a support, a bolt movable thereon, means for retracting the bolt, comprising a handle-operated member mounted for rotation in said support, a rotatable member having an eccentric portion, and a member movable by rotation of said eccentric portion into position to lock said handle-operated member in unoperated position.

4. In a door latch, the combination of a support, a bolt movable thereon, means for retracting the bolt, comprising a handle-operated member mounted for rotation in said support, a member mounted for rotation about a horizontal axis comprising a crank and crank pin, and a member movable by rotation of said pin into substantially its upper dead center position to lock said handle-operated member against movement to retract the bolt.

5. In a door latch, the combination of a support, a bolt movable thereon, means for retracting the bolt, comprising a handle-operated member mounted for rotation in said support, a member carrying a pin mounted for rotation about a horizontal axis, and a pivoted member having a slot

therein into which said pin extends, said last named member and said handle-operated member having portions adapted to contact to lock said handle-operated member against movement to retract the bolt when said pin-carrying member is operated.

6. In a door latch, the combination of a support, a bolt movable thereon, means for retracting the bolt, operable from one side of the door, comprising a handle-operated member mounted for rotation in said support, and having a lateral extension, and a pivoted member normally out of the path of said extension, said pivoted member and extension having, one, a projection, and the other, a recess, said pivoted member being operable from the other side of the door to bring said projection and recess into locking engagement with each other.

20 7. In a door latch, the combination of a support, a bolt movable thereon, means for retracting the bolt, comprising a handle-operated member mounted for rotation in said support, and having a lateral extension thereon, and a pivoted member, said extension and pivoted member having, one, a recess, and the other, a projection, said projection being adapted to enter the recess when said handle-operated member is in its normal unoperated position and when said pivoted member is swung from its normal unoperated position, said pivoted member being so positioned, when swung to cause said projection to enter said recess, that effort to turn said handle-operated member will transmit stress through said pivoted member to the pivot thereof without any substantial turning effect on said pivoted member.

40 8. In a door latch, the combination of a support, a bolt movable thereon, means for retracting the bolt, comprising a handle-operated member mounted for rotation in said support, and having a lateral extension thereon, and a pivoted member, said extension and pivoted member having, one, a recess, and the other, a projection, said projection being adapted to enter the recess when said handle-operated member is in its normal unoperated position and when said pivoted member is swung from its normal unoperated position, said pivoted member being so positioned, when swung to cause said projection to enter said recess, that effort to turn said handle-operated member will transmit stress through said pivoted member in the direction of the pivot thereof, and a separate hand operated member for moving said pivoted member into and out of its locking position, arranged to remain in set position when moved to operate said pivoted member, and also when moved to swing

said pivoted member back into its normal unoperated position.

9. In a door latch, the combination of a support, a bolt movable thereon, a hand lever pivoted to said support and adapted to retract the bolt, a roller bearing carried by said hand lever, and a handle-operated member mounted for rotation in said support and having a portion adapted to engage and rotate said roller-bearing and swing said hand lever back to retract the bolt, when said member is rotated.

10. In a door latch, the combination of a support, a bolt movable thereon, a hand lever pivoted to said support and adapted to retract the bolt, a roller-bearing carried by said hand lever, and a handle-operated member mounted for rotation in said support and having portions on opposite sides of the axis thereof, adapted respectively to engage and rotate said roller bearing and swing said hand lever back to retract the bolt, when said member is rotated in one direction or the other.

11. In a door latch, the combination of a support, a bolt movable thereon, a hand lever pivoted to said support and adapted to retract the bolt, a roller-bearing carried by said hand lever, and a handle-operated member mounted for rotation in said support and having portions on opposite sides of the axis thereof, having surfaces curved towards said hand lever, and a surface between said two surfaces, curved away from said hand lever, said last named surface being adapted to engage said roller bearing when said member is in its normal unoperated position and said first named surfaces being adapted, respectively, to engage said roller bearing when said member is rotated in one direction or the other, to move said hand lever to retract the bolt.

12. In a door latch, the combination of a support, a bolt movable thereon, a hand lever pivoted to said support and adapted to retract the bolt, said lever having a forwardly curved projection, a handle-operated member in front of said lever, mounted for rotation in said support, having an inwardly curved centrally positioned surface normally engaged by said projection and surfaces on either side thereof adapted respectively to engage and wipe over said projection, when said member is rotated in one direction or the other, to move said lever to retract the bolt, and a spring pressing said hand lever towards said member.

In testimony whereof I have signed my name to this specification, at Bridgeport, Conn., on this 25th day of April 1922.

RAYMOND G. MOORE.
